UNITED STATES PATENT OFFICE.

JAMES R. HICKS, OF KANSAS CITY, MISSOURI.

ROTARY HARROW.

SPECIFICATION forming part of Reissued Letters Patent No. 10,868, dated September 27, 1887.

Original No. 325,832, dated September 8, 1885. Application for reissue filed February 14, 1887. Serial No. 227,619.

To all whom it may concern:

Be it known that I, JAMES R. HICKS, a citizen of the United States, residing at Kansas City, in the county of Jackson and State of Missouri, have invented certain new and useful Improvements in Rotary Harrows, of which the following is a description.

This invention relates to that class of harrows which are journaled to revolve about vertical axes; and it has, for its object to keep corn or cotton stalks down among the harrow-teeth, to break the stalks, and to prevent their running up through the harrow to entangle it and to endanger the rider. Its object is, further, to so hang a pair of rotary harrows that either harrow may remain fixed on the ground while the other revolves around it in turning corners, and to insure the revolving of the harrow when advancing on the field.

20 To this end my invention consists in the construction and combination of parts forming a harrow, hereinafter described and claimed, reference being had to the accompanying drawings, in which—

25 Figure 1 is a front elevation of my harrow. Fig. 2 is a plan view of the same; and Fig. 3 is a side elevation of one harrow, showing the cross-beam in section.

30 A represents the frame of two harrows, which may be of any usual form; but I prefer to give them a radial form from the center of each, and to fix the teeth B to project downward therefrom. These arms of each frame are surmounted with a disk, C, which is secured firmly to all the arms, thereby becoming a part of each frame, tending to make it 35 very strong. Both of these harrows are pivoted to revolve on bolts D, which pass up through a cross-beam, E, on which the rider's 40 seat, F, is fixed.

45 G are draft-bars pivoted upon the bolts D between the harrows and cross-bar, and extending their clevises P sufficiently beyond the circumference of each disk to keep the team attachments free of the harrows, whether the team is pulling straight ahead or turning a corner. In the latter case one harrow may remain fixed in the ground while the other turns around it, the draft-bars swinging around their 50 pivotal attachments sufficiently to remain in line with the draft of the team and to draw

straight from the center of each harrow in any direction.

H H represent rollers journaled in forked rods I, which slide vertically through the cross-beam E, and are pressed downward by springs J, acting between a collar, K, on each rod, and a vertically-adjustable yoke, L. This yoke is attached to the cross-beam by means of adjusting screw-bolts M, whereby more or less 55 tension may be exerted on the springs and through them on the rollers. The rollers tend to depress the two harrows at their adjacent sides, which depressing causes the teeth at those sides to bury deeper in the ground than 60 the teeth at the other sides do, thereby retarding the depressed sides and causing the two harrows to rotate by the act of advancing the machine. The disks serve as hoods to keep 65 corn and cotton stalks down among the harrow-teeth, where the stalks will be broken up, and in so doing they prevent the stalks from entangling the harrows and from pushing up through the harrows and endangering the 70 driver.

75 I am aware that a rotary harrow-frame has been acted upon at one side by a roller attached to a horizontal arm having a limited degree of elasticity without means for effecting the adjustment of its tension, and this I 80 do not claim.

What I claim as my invention, and desire to secure by Letters Patent, is—

1. The combination of the cross-beam E, two harrows vertically journaled thereto, a 85 circular hood covering the top of each harrow, forked rods I, fitted to slide vertically through the beam E, rollers H, journaled in the forked rods above and in contact with the said hoods to roll thereon, the yokes L, above the beam 90 E, the springs J, acting between the yokes and shoulders upon the rods I to press the rollers H upon the hoods, and adjusting screw-bolts M, securing the yokes to the cross-beam, substantially as shown and described.

2. In a harrow, the combination of a draft-frame, the toothed harrow-frame connected thereto by a perpendicular pivot, around which it is free to rotate, a roller bearing on one side of the harrow-frame, a vertical rod carrying 95 said roller and extended thence upward through guides on the draft-frame, and a spiral 100

spring encircling said rod and urging the same downward.

3. In a harrow, the combination of a draft-frame, a rotary toothed frame connected thereto by a vertical pivot, a vertically - sliding rod carried by the draft-frame, a roller attached to the lower end of said rod and bearing on the rotary frame, a spring applied to the upper end of said rod, an adjustable yoke for regulating the tension of said spring, and an adjustable collar, K, to control the downward movement of the rod, whereby the tension of the spring and the inclination of the harrow-frame may be regulated independently of each other.

15

4. The combination of the draft-frame, the two toothed harrow-frames connected thereto by upright pivots, on which they are free to rotate, the rollers bearing on the inner sides of the respective harrow-frames, the sliding rods mounted on the draft-frame and carrying said rollers, and the springs acting to urge said rods downward, whereby the frames are caused to revolve inward toward each other when the machine is in motion.

JAMES R. HICKS.
